MAX PFAU, OF WOODSTOCK, ILLINOIS, ASSIGNOR TO THE EMERSON TYPEWRITER CO., OF WOODSTOCK, ILLINOIS, A CORPORATION OF ILLINOIS.

TYPE-BAR MOUNTING.

1,018,986.

Specification of Letters Patent. Patented Feb. 27, 1912.

Application filed April 14, 1911. Serial No. 621,107.

To all whom it may concern:

Be it known that I, MAX PFAU, a citizen of Saxony, Germany, residing at Woodstock, in the county of McHenry and State 5 of Illinois, have invented certain new and useful Improvements in Type-Bar Mountings, of which the following is a specification.

The present invention relates to a form 10 of mounting used in positioning a type bar upon the body of a typewriting machine, and to the arrangement of the tension mechanism utilized in returning the type bar to normal position.

15 The objects of the present invention are, to provide a mounting for the type bar which will insure against a loosening and rattling of the same during operation, as well as to prevent a movement of the type 20 bar out of the desired line of travel during operation.

Another object of the invention is to provide a tension member which can be easily and quickly adjusted for the purpose of 25 varying the tension upon the type bars.

A further object of the invention is to eliminate the screw-threaded members usually employed for the purpose of adjusting this spring tension. And a still 30 further object of the invention is to provide a rail in which the members are mounted which adjust the tension of the spring controlling the movements of the type bar, and to so position this rail that it will serve as 35 a reinforcement for the type supporting frame.

The invention further consists in the features of construction and the combination of parts hereinafter described and claimed.

40 In the drawings, Figure 1 is an elevation of a type supporting frame of the present invention, showing type bars connected thereto which are equipped with the devices of the present invention; and Fig. 2, a view 45 showing a type bar with the appliances of the present invention thereon, and showing, in sections, the rails in which said bar is mounted.

In the typewriter art, it is necessary to 50 provide a framework in which the type bars are mounted, and it is necessary to so mount the type bars within the framework that accommodations may be made for the subsequent wearing of the bearings, so that

loosening of the bar in its mounting will 55 not result. This loosening is objectionable for several reasons, among the principal being that it results in a rattling of the bearing during the operation of the machine, and also results in an incorrect movement 60 of the bar, which may cause the type to misalign in the writing operation. It is further necessary to provide some tension acting means for returning the type bars to normal position after they have been thrown 65 forward and have completed the writing operation. It is deemed expedient to provide some means for adjusting this spring tension so that the bar may be returned to its normal position at the proper speed. 70 If too great a spring tension is placed upon the bar, it may result in the bar returning before it has fully completed its stroke, and hence the character is not imprinted. If the bar is returned too slowly, it may result in 75 the next successively acting bar striking the former bar before it returns, and hence a piling of the type result. It is, therefore, essential, in order to properly perform the writing operation, to adjust the spring tension on the type bar so as to give to it the proper speed of return to normal position.

Referring to the drawings, there is shown a type supporting frame 3, which may be of any suitable form and size, the particular 85 form shown being for illustrative purposes only. The type bar frame, as shown, consists of an upper rail 4 and a lower rail 5. Mounted within these rails are a series of type bars 6, which also may be of any suitable size and formation, the particular style shown being merely for illustrative purposes. The type bars are provided with an upper cone bearing 7 and a lower cone bearing 8, each of these cone bearings being 90 mounted within suitable recesses within the respective rails.

The use of a cone bearing in a swinging type bar is deemed to be an important item, since by means of this particular form, the 100 wearing away of the bearing within the rail can be compensated for and the bearing always maintained firm and rigid. It is, of course, understood in the mechanical art that a cone bearing can be very easily adjusted so as to bring it to a firm seat in the member in which it is mounted.

Each of the lower cone bearings 8 termi-

nates in a slotted stem 9; and secured to the lower end of the frame 3 is a rail 10, as shown, of channel formation. Mounted within this rail 10 are a series of pins 11, each consisting of a body portion 12 terminating in a reduced stem 13, the reduced stems each being provided with a notch similar to the notch in the stems 9. The body portions 12 are split, as at 14, so that they consist of what may be termed leaves 15. The material of which these pins are formed is of such a nature as to give to the leaves a spring property; that is, they are formed so as to normally extend in a direction divergent from one another, being spread apart at their lower ends.

The upper flange of the rail 10 is provided with openings 16, through which the reduced ends 13 of the pins 11 extend; and the lower flange of the rail 10 is provided with openings 17, through which the body portion of the pins extends. The leaves 15 of the pins are sprung together when they are inserted within the openings 17, so that they spring against the side walls of said openings and are held against displacement therefrom by spring tension or friction. It will be noted that the ends of the pins 11 project slightly beyond the rail. This is to permit of the lower portion of the slot in the body portion extending into a position where a tool can be inserted therein for the purpose of revolving the pin within the rail 10. The spring tension on the leaves 15 is sufficient to prevent the pins 11 from becoming displaced from the rail 10 and to prevent rotative movement of the pins within the rail under ordinary conditions of usage.

Interposed between the adjacent ends of the pins 11 and the stems 9 are tension members 18, which, as shown, are in the form of helically coiled springs having one free end inserted within the slot in the reduced end 13 of the pins 11. These tension members control the return movements of the type bars, and they are regulated so as to increase or decrease the degree of their tension property in the following manner: A tool is inserted in the lower end of the slot or recess in the body of the pins 11, and the pin is revolved within the rail 10. The type bars are held against swinging movement during such revolution of the pin. The stem 9 on the type bar will remain fixed and the reduced end 13 of the pin 11 will be revolved. This, of course, results in the winding up the spring 18, and hence the increasing of the tensional powers thereof. The pins are held sufficiently rigid by friction, so that the power of the spring will not turn them in the bearings in the rail 10. If the tension power is desired to be decreased, the pin 11 will, of course, be revolved in a reverse direction. The spring

property of the leaves 15 is sufficient to hold said pins against revolution simultaneously with the revolution of the type bar, so that as the type bar is swung, the stem 9 thereon will revolve and the pin 11 will be stationary. Hence, during the revolution of the type bar, the spring is wound up to a greater degree than the initial winding given to it by the manipulation of the pin 11, and the tension created in the spring by the revolving of the type bar will serve to return the type bar to normal position. Obviously, dependent upon this tensional strength is the speed of return movement of the type bar, and so the greater or less initial strength placed in the spring will determine the speed of movement with which the type bar is returned, and, as heretofore explained, this initial strength can be determined by an adjustment of the pin 11.

It will be noted that in the present construction all of the screw-threaded members for the purpose of regulating the spring tension on the type bar are eliminated. It will be further noted that by utilizing the bar 10, which extends from side to side of the type supporting frame, this bar serves to strengthen and increase the rigidity of the frame.

I claim:

1. In combination with a vertically extending swinging type bar, a mounting for said bar, an adjustable member spaced away from the lower end of the bar and extending approximately parallel therewith, and a tension member having one end attached to the lower end of the type bar and its other end attached to the adjustable member, substantially as described.

2. In combination with a swinging type bar, a mounting for said bar, an adjustable member held by friction against rotative movement with the bar, a tension member having one end attached to the lower end of the type bar and its other end attached to the adjustable member, and a rail in which the adjustable member is mounted, substantially as described.

3. In combination with a swinging type bar, a mounting for said bar, a frictionally-held rotatable pin-like member spaced away from the lower end of the bar and held by friction against rotative movement with the bar, and a tension member having one end attached to the lower end of the type bar and its other end attached to the pin-like member, substantially as described.

4. In combination with a swinging type bar, a mounting for said bar, a frictionally-held rotatable pin-like member spaced away from the lower end of the bar and held by friction against rotative movement with the bar, a tension member having one end attached to the lower end of the type bar and its other end attached to the pin-like mem-

- ber, and a bar of channel formation in which the pin-like member is mounted, substantially as described.
5. In combination with a swinging type bar, a mounting for said bar, a pin having a split body portion lying below said bar, a rail in which said pin is mounted, the split formation of said pin tending to hold it within said rail by frictional engagement, 5
10 said pin having a notched end, and a tension member having one end attached to the type bar and its other end attached to the notched end of the split pin, substantially as described.
- 15 6. In combination with a swinging type bar, a mounting for said bar, an adjustable member normally held by friction against movement with respect to the swinging movement of said type bar, and a tension 20 member having one end attached to the type bar and the other end attached to said adjusting member, and adapted to be wound and unwound in accordance with the movements of the type bar, substantially as de- 25 scribed.
7. In combination with a swinging type bar, a mounting for said bar, an adjustable
- member normally held by friction against movement with respect to the swinging movement of said type bar, a tension member having one end attached to the type bar and the other end attached to said adjustable member, and a rail in which said adjustable member is mounted, substantially as described. 30
8. In combination with a swinging type bar, a mounting for said bar, a split pin, a mounting for said pin, whereby it is held by frictional engagement against rotative movement with said bar, and a tension member having one end secured to the pin and the other end secured to the type bar, substantially as described. 35
9. In combination with a swinging type bar, means for returning the bar to normal position, consisting of a coil spring depending therefrom, and means for winding and unwinding said spring to regulate the tension on said bars, substantially as described. 40 45
